UNITED STATES PATENT OFFICE.

HEINRICH GERDES, OF BERLIN, GERMANY, ASSIGNOR TO SAFETY CAR HEATING AND LIGHTING CO., OF NEW YORK, N. Y.

STEAM-HEATING APPARATUS FOR VEHICLES.

No. 836,317.

Specification of Letters Patent.

Patented Nov. 20, 1906.

Application filed October 20, 1902. Serial No. 128,035.

To all whom it may concern:

Be it known that I, HEINRICH GERDES, a subject of the German Emperor, residing at Berlin, Germany, have invented a certain new and useful Steam-Heating Apparatus for Vehicles, of which the following is a description.

The present invention relates to steam-heating apparatus for vehicles; and its object is to regulate the steam-feed to the heating-bodies by the temperature in the compartments.

The invention comprises the features of construction and arrangement and combination of parts hereinafter described, and particularly set forth in the appended claims.

The apparatus may be used in connection with both high and low pressure steam-heating systems; but in the latter case a reducing-valve has to be employed.

In order to render the present specification easily intelligible, reference is had to the accompanying drawings, in which similar characters of reference denote similar parts throughout the several views.

Figure 1 is a vertical longitudinal section through a railway-car provided with the steam-heating plant. Fig. 2 is a horizontal section; and Fig. 3 is a horizontal section through the car, showing the seats and flooring removed in one compartment in order to clearly show the location of the pipe connections, radiators, and other apparatuses comprising the whole plant. Fig. 4 is a sectional front elevation of the device mounted in each compartment and operated by the temperature therein, which device serves to control the compressed-air feed to the steam-valve piston. Fig. 4^a is an elevation of the steam-feed-controlling valve and its piston-housing, showing the pipe connections from the air-feed-controlling device to the said piston-housing. Fig. 4^b is an end elevation of the construction in Fig. 4^a. Fig. 5 is a section on line A B of Fig. 4^a, and Fig. 6 a section on line C D of Fig. 4^a. Fig. 7 is a detail sectional view of the four-way valve.

I will first describe the general arrangement of the plant with reference to Figs. 1 to 3. The invention is illustrated and described in connection with a low-pressure steam-heating plant. The main pipes *c* for the steam heating are arranged underneath the car in the usual manner. The radiators

h for the various compartments 1, 2, 3, &c., 55 are generally mounted underneath the seats and connected up by pipes *m* and the housing *A* of the steam-feed-controlling device, herein-after described, to the branch steam-pipe *a*, said housing *A* being connected to the pipe *a* 60 by means of the coupling *a'*. Between the main and branch pipes *c* and *a* at the end of each car a reducing-valve *R* is provided, which is advantageously adjusted to reduce the pressure from the steam-main *c*, so as to 65 enable the steam or condensed water to flow off freely from the last radiator of the car up through the pipe *e* or down through the water-drain at *T* practically at atmospheric pressure. The pressure in the branch pipe *a* 70 must be sufficient at all times to force the steam into and through the last radiator of the car. The compressed air for operating the controlling-piston of the steam-feed valve may be taken from the air-brake main 75 *b*, or a special compressed-air conduit may be provided, which may be fed from a compressed-air reservoir *H*, or the latter may serve as an auxiliary holder for the air-brake main. The compressed-air pipes *l* and *l'*, 80 controlled by the contraction and expansion of the ether acting on the mercury, lead from the apparatus *S* in the compartments to each end of the housing *s* of the piston which controls the steam-feed valve. The 85 radiators are drained of the condensed water through the drainage-pipe *d*, which is provided at the end with a funnel *T*.

The device *s* for controlling the compressed air-feed to the steam-valve-controlling piston is constructed in the following manner: The spirally-wound tube *f*, Fig. 4, is mounted in the housing *x* and has its upper end tightly closed, the lower end being in open communication with the mercury-receptacle *g*. The bottom of the receptacle communicates, by means of a pipe *i*, with the bottom of a cylinder *k*, having therein a piston *n*. This piston is sufficiently heavy or loaded so as to follow the mercury by gravity when it sinks. A four-way cock *q* is mounted in the upper part of the housing *x*, and its plug-arm is linked at *p* to the upper end of the piston-rod *o* of the piston *n*. The length of the piston-rod *o* is adjustable in 100 any suitable manner. The four-way cock *q* is connected up by pipe *r*² to the compressed-air main *b* and also by means of

branch pipes l l' to the opposite ends of a housing s , Figs. 4^a and 6, in which the double piston t is free to move. As illustrated in Fig. 7, the cock q is a four-way cock, the plug 5 of the same being provided with two pairs of ports q' q^2 and q^3 q^4 , arranged in different planes of the cock and communicating, respectively, with the four ports or channels 1 2 4 and 1 3 4 of the cock-housing. Channel 2 10 communicates with pipe l , channel 3 with pipe l' , channel 4 with pipe r^2 , and channel 1 with pipe r^3 , or the relief-channel. Thus when the plug is in the position shown in Fig. 7 the pipe l is in communication with the pressure 15 medium from pipe r^2 and pipe l' is relieved of pressure through channel 3, port q^3 , and pipe r^3 . In the opposite position of the lever p the pipe l' will be in communication with the pressure-supply by means of port q^4 , and pipe 20 l will be relieved of pressure by means of port q^2 . The spindle u' passes through the wall of the housing s and engages in the end of the plug v of the steam-distributing valve w , Fig. 5. Within the housing s the spindle 25 u' carries the arm u , the roll u^2 of which engages a slot t' of the double piston t , so that any movement of the latter will be communicated to the plug v of the steam-distributing valve w ; which will be gradually closed 30 or opened accordingly. This valve distributes steam from the secondary pipe a through the branch pipes m to the radiators h , mounted underneath the seats of the compartments. 35

In order to attain a reliable working of the piston t , which might not take place if the compressed air were fed directly to the housing s of the same, the ends of the housing s at each side of the piston are provided with annular jackets s' , into each of which one of the 40 pipes l and l' leads. These jackets are filled with oil, and the compressed air entering one or other of the pipes l or l' forces the oil into the corresponding end of the cylinder, and thus operates the piston t . This arrangement tends to keep the piston tight and prevent leakage and facilitates working of the 45 same.

The coupling-flanges S' are for coupling up the pipe connections m m to the valve W , 50 while the flanges a^x are for coupling the valve to the main steam-supply pipe a , as will be readily understood from the Fig. 3.

The ports referred to in line 8 of claim 2 are shown at 22, Fig. 6.

55 The operation of the whole plant takes place in the following manner: If the temperature in the compartment rises above the normal height, the tension of the ether-vapor in the spiral tube f increases correspondingly 60 and forces the mercury in the receptacle g through pipe i into the cylinder k , thus raising the piston or plunger n . The rod o consequently turns the plug of the four-way cock q and allows compressed air to flow from the 65 supply-pipe r^2 , through the pipe l , to the cor-

responding jacket s' , thus forcing the oil against the corresponding end of the piston t and moving the same. This causes the arm u to turn the plug v of the steam-distributing valve w and shut off or reduce the steam fed 70 to the radiators of the compartment in question. If the temperature in the compartment sinks below the normal degree, the opposite action takes place. The ether in the spiral tube f contracts, the mercury sinks in the pipe i and cylinder k , and the piston n follows it by gravity. This throws the plug of the four-way cock q round in the opposite direction, admitting compressed air to the pipe l' and oil to the corresponding side of 80 the piston t , which now acts to open the steam-distributing valve instead of closing it, so that more steam may pass to the radiators of the compartment in question.

The indirect operation of the steam-valve, 85 by the aid of a small distributing device and compressed air is rendered necessary because the sensitive apparatus has to be mounted in the compartment, while the steam-distributing valve is mounted beneath the car, so 90 that the direct operation of the parts from the apparatus in the compartment is practically impossible. In addition to this, more power is necessary for working the steam-valve than could be derived from the sensitive 95 apparatus, unless the dimensions of the same were increased to an impracticable extent.

I claim as my invention—

1. In a train-heating plant, the combination of a steam-pipe system having a distributing-cock for each compartment to be heated, a cylinder having a double piston and mounted in proximity to each of the said distributing-cocks, a source of compressed fluid, a thermostat in the compartment, and a four-way cock having suitable connections to render it operable by the thermostat, pipe connection from the said four-way cock to the source of compressed fluid and to each end of the said cylinder, and means in connection with the double piston of the cylinder to operate the distributing-cock in the manner and for the purpose substantially as described. 100

2. In a train-heating plant, the combination of a steam-pipe system having a distributing-cock for each compartment to be heated, a double-piston cylinder for each cock and means for operating said cocks when the respective pistons are moved, a source of compressed fluid, a thermostat in the compartment and means operated thereby to pass the compressed fluid to one or other end of the said cylinder, a jacket to the said cylinder and a liquid therein and ports at each 115 end of said cylinder to allow the liquid to enter at either end of the cylinder substantially as described. 120

3. In a train-heating plant, the combination of a steam-pipe system having a distrib- 130

utting - cock for each compartment to be heated, a double-piston cylinder for each cock and means for operating said cocks when the respective pistons are moved, a 5 source of compressed fluid, a thermostat in the compartment a four-way cock operated by said thermostat, and pipe connections between it and the source of compressed fluid and between the four-way cock and each end 10 of the said cylinder so that when the four-way cock is turned in one or the other direc-

tion, one end of the cylinder will be opened up to the pressure fluid, and the pipe from the other end will be opened up to the outer air substantially as described. 15

In witness whereof I have hereunto set my hand in presence of two witnesses.

HEINRICH GERDES.
